UNITED STATES PATENT OFFICE.

LESTER KULP, OF CHICAGO, ILLINOIS, ASSIGNOR TO KULP THEFTPROOF LAMP COMPANY, OF CHICAGO, ILLINOIS, A CORPORATION OF ILLINOIS.

LAMP-LOCKING MEANS.

Application filed April 23, 1924. Serial No. 708,479.

This invention relates to lamp locking means or devices for rendering electric lamp bulbs theftproof and has particular reference to devices of this character wherein the locking mechanism is entirely embodied in the lamp structure and which may be, if desired, used with the ordinary types of sockets or receptacles.

An important object, therefore, of my invention is to provide an electric lamp so made that it may be inserted into a socket of the usual construction and yet which cannot be stolen or removed from such socket until after the bulb has become broken.

15 A further object of this invention is to provide means whereby a lamp bulb may be inserted into a receptacle member by turning movement, but such means being displaceable or capable of being rendered ineffective upon an attempt being made to remove the lamp from its receptacle by a turning movement.

Another aim of this invention is to provide a theftproof lamp in which the electrical connections do not become broken or distorted when the bulb is tampered with. A common difficulty of devices of this character as previously made has been that the electrical connections to the lamp become destroyed upon an attempt being made to remove the bulb from its socket. This, of course, results in rendering the lamp useless whether stolen or not.

Further objects of this invention comprise the use of a very simple, durable and inexpensive construction for the purposes named which also embodies substantially the minimum number of parts and which, if desired, may embody a lamp bulb member of standard construction.

40 In the accompanying drawing, which illustrates an embodiment of my invention,

Figure 1 is a perspective view illustrating the various separated parts embodied in the same;

Fig. 2 is a central sectional view through the base of a lamp embodying this invention and showing the parts in assembled relationship; and,

50 Fig. 3 is a detail sectional view of a portion of the lamp base member and shell contact.

55 In general, the invention as illustrated may comprise an electric lamp bulb 10 of the standard construction, a base member 11

adapted to be securely cemented upon the stem or neck 12 of the lamp bulb and the threaded shell contact 13 for embracing the base member 11.

The base member 11 may comprise a cylindrical shell contact 14 upon which the threaded shell contact 13 is loosely fitted. The shell contact 14 may be provided with one or more struck-up spring dog members as at 15, which are for the purpose of engaging depressed or inwardly struck portions as at 16, formed upon the shell contact 13.

From an inspection of Figs. 1 and 3, it will be observed that when the base member 11 is rotated in a clockwise direction for inserting the lamp into a receptacle the dog 15 will engage the struck down portion or lug 16 and as a consequence will exert rotational force upon the threaded shell contact 13. In this manner, the threaded shell contact may be screwed into the receptacle. However, when an attempt is made to rotate the lamp in a counterclockwise direction for withdrawal from the socket, the dog 15 upon striking the lug 16 will become displaced from its outwardly bent position and will spring inwardly sufficient to allow the lug 16 to pass. Thus the threaded shell contact 13 will not be forced to rotate in this direction with the base member 11. Accordingly, the threaded shell contact cannot be screwed out of the receptacle and as a result the lamp is rendered theftproof.

The threaded shell contact is permanently retained against longitudinal movement in respect to the lamp by means of inturned flanges 17 and 18, located at the respective ends of the threaded shell contact 13. The flange 17 is adapted to be spun over and to abut a flange portion 19 at the upper edge of the base member 11. The flange 18 is adapted to be spun over a beaded portion 20 formed upon the base member near its lower edge.

From an inspection of Fig. 2 it will be observed that the lower portions of the flange 18 may be located at a point which will be well within the receptacle member in which the lamp may be inserted. In this way the receptacle member serves to prevent access to the threaded shell contact member and accordingly, this member cannot be turned either inwardly or out of the receptacle by tampering, while the lamp is in op-

erative condition. However, after the lamp has become worn out, the operator may place a canvas or other bag over the glass portion of the lamp and thereupon break the lamp. 5 This canvas bag will retain the particles of broken glass. Access may then be had to the flange edge 18 for removal of the lamp by pliers or other suitable tools.

- As shown in Fig. 2, the interior of the 10 base member 11 may be filled with a suitable cement as at 21 and the beaded portion 20 will cooperate with the rib 22 on the lamp bulb to securely lock the lamp bulb stem in the cement and within the base member 11.
- 15 At the upper end of the base member 11 a center contact 23 may be positioned and held in place by the use of an insulating end piece 24, which is tightly fitted or molded into the upper end of the base member 11. As indicated in Fig. 2, an inwardly directed beaded portion 25 may be formed in the base member 11 for engaging and holding the insulating end piece 24.
- 20 The center contact 23 may comprise a disc shaped member having a portion of its periphery struck up to form a spring contact piece 26 and with its central portion punched and struck down to form an eyelet at 27 for engaging an opening 28 in the insulation piece 24 and for receiving one of the lamp lead wires 29 which may be soldered therein. The other lamp lead wire 30 may pass upwardly through the insulation piece 24 and may be soldered to a perforated lug as indicated at 31 in Fig. 1. The perforated lug 31 preferably is positioned in a depression 32 formed in the insulation piece 24 in order that its surface will be below that of the insulation. This construction will permit the 35 lead wire 31 to be soldered at the perforation in the lug 31, but without causing the parts of this connection to protrude beyond the surfaces of the base member.
- 25 In assembling the device, the base member 11 including the threaded shell contact 13 may be, if desired, first completely assembled independently of the lamp bulb. The inner lower edge of the face of the base member 11 may be covered with unbaked cement which is to be used to fix the lamp bulb in position therein. This cement may 40 comprise a mixture including a phenol condensation product which will upon baking greatly expand, substantially filling the interior of the shell as indicated in Fig. 2. After the base has been provided with the unbaked cement, the lamp bulb stem with its lead wires may be inserted and soldered in place. It will be noted that the eyelet portion 27 of the contact 23 and the perforated lug 31 are conveniently placed so that the lead wires may be directly inserted with very little difficulty. After the lead wires 45 are in place, the lamp base may be subjected to a temperature sufficiently high to bake the

cement, thus permanently fixing the base in position on the lamp bulb stem.

While I have shown and described one specific embodiment of my invention, it is understood that I do not desire to have any 70 limitations imposed thereupon except as specifically set forth in the appended claims or required by the prior art, since mechanical expedients or equivalents of the various elements are intended to come within the 75 scope of my invention.

Having thus described my invention, what I claim as new and desire to secure by Letters Patent of the United States, is:

1. An incandescent lamp consisting of a 80 bulb member, a center contact therefor, a pair of concentric substantially coextensive and cylindrical shell contact members surrounding the stem of said bulb, and fixed against longitudinal movement in respect 85 to each other, the inner one of said shell contacts being secured as by cement to the bulb stem, the outer shell contact being threaded for engagement with a conventional receptacle, said shell contacts being 90 provided with ratchet means preventing rotation of said bulb in respect to the outer one of said shell contacts in one direction only to permit insertion but being ineffective for removal of the lamp in respect to a 95 receptacle by turning the bulb, and means for maintaining electrical connection between the filament of the bulb and said shell and center contacts regardless of possible rotational movement of the bulb with respect to the outer shell contact. 100

2. An electric lamp comprising a bulb, a threaded shell contact therefor, means permanently fixing said shell contact against longitudinal movement in respect to said 105 bulb, ratchet means preventing rotation of said bulb in respect to said shell contact in one direction only to permit insertion but to prevent removal of the shell contact in respect to a receptacle by turning said bulb, 110 and means for supplying electrical energy to the lamp through said contact regardless of such rotation.

3. In combination, an enclosure for electrical apparatus, a pair of concentric substantially coextensive and cylindrical shell contacts mounted on said enclosure, and fixed against longitudinal movement in respect to each other, the outer contact being provided with means for engaging a conventional electrical receptacle solely by turning movement of said shell contact, the inner one of said shell contacts being secured as by cement to the enclosure, ratchet means preventing relative rotation of said shell 115 contacts in one direction only to permit insertion of the shell contact in respect to a receptacle by turning said enclosure. 120

4. In combination, an enclosure for electrical apparatus, a cylindrical shell mounted 130

- on said enclosure, said shell being provided with means for engaging a supporting receptacle by turning movement of said shell, means permanently fixing said shell against longitudinal movement in respect to said enclosure, and ratchet means preventing rotation of said enclosure in respect to said shell in one direction only to permit insertion but to prevent removal of the shell in respect to a receptacle by turning said enclosure.
5. In combination, an electric lamp member including a bulb, a shell contact and an insulated center contact therefor, means permanently fixing said shell contact against longitudinal movement in respect to said bulb, said lamp member being provided with a resilient dog, means on said shell contact for engaging said dog to prevent rotation of said bulb in respect to said shell contact in one direction only to permit insertion but to prevent removal of the shell contact in respect to a receptacle by turning said bulb, a filament in said bulb, and means for maintaining electrical connection between said filament and said shell and center contacts regardless of the rotation of the bulb with respect to the shell contact.
6. In a device of the type described, an electric lamp bulb, a base therefor comprising a metallic substantially cylindrical shell permanently fixed to the stem thereof, and a cylindrical contact embracing said shell and retained against longitudinal movement in respect thereto, said shell being formed with a resilient ratchet dog protruding outwardly of the base and said cylindrical contact being formed with a stamped portion for engaging said ratchet dog for preventing rotation of said bulb in respect to said shell contact in one direction only to permit insertion of the contact in respect to a receptacle by turning the bulb.
10. In an electric lamp, a bulb of conventional construction, a cap member permanently fixed upon the stem thereof, and a shell contact embracing said cap member and retained against longitudinal movement thereupon and against rotation in respect thereto in one direction only.
15. In combination, an enclosure for electrical apparatus, a pair of concentric substantially coextensive and cylindrical shell contacts mounted on said enclosure and fixed against longitudinal movement in respect to each other, the outer contact being provided with means for engaging a conventional electrical receptacle solely by turning movement of said shell contact, the inner one of said shell contacts being secured as by cement to the enclosure and formed with a resilient ratchet dog protruding outwardly of the periphery thereof, and said outer contact being formed with a stamped portion for engaging said dog for preventing rotation of said enclosure in respect to said outer contact in one direction only to permit insertion of the contact in respect to a receptacle by turning the enclosure.
20. In combination, an electric lamp member including a bulb, a shell contact and an insulated center contact therefor, means permanently fixing said shell contact against longitudinal movement in respect to said bulb, said lamp member being provided with a resilient dog, means on said shell contact for engaging said dog to prevent rotation of said bulb in respect to said shell contact in one direction only to permit insertion but to prevent removal of the shell contact in respect to a receptacle by turning said bulb, a filament in said bulb, and means for maintaining electrical connection between said filament and said shell and center contacts regardless of the rotation of the bulb with respect to the shell contact.
25. In combination, an enclosure for electrical apparatus, a pair of concentric substantially coextensive and cylindrical shell contacts mounted on said enclosure and fixed against longitudinal movement in respect to each other, the outer contact being provided with means for engaging a conventional electrical receptacle solely by turning movement of said shell contact, the inner one of said shell contacts being secured as by cement to the enclosure and formed with a resilient ratchet dog protruding outwardly of the periphery thereof, and said outer contact being formed with a stamped portion for engaging said dog for preventing rotation of said enclosure in respect to said outer contact in one direction only to permit insertion of the contact in respect to a receptacle by turning the enclosure.
30. In combination, an electric lamp member including a bulb, a shell contact and an insulated center contact therefor, means permanently fixing said shell contact against longitudinal movement in respect to said bulb, said lamp member being provided with a resilient dog, means on said shell contact for engaging said dog to prevent rotation of said bulb in respect to said shell contact in one direction only to permit insertion but to prevent removal of the shell contact in respect to a receptacle by turning said bulb, a filament in said bulb, and means for maintaining electrical connection between said filament and said shell and center contacts regardless of the rotation of the bulb with respect to the shell contact.
35. In combination, an enclosure for electrical apparatus, a pair of concentric substantially coextensive and cylindrical shell contacts mounted on said enclosure and fixed against longitudinal movement in respect to each other, the outer contact being provided with means for engaging a conventional electrical receptacle solely by turning movement of said shell contact, the inner one of said shell contacts being secured as by cement to the enclosure and formed with a resilient ratchet dog protruding outwardly of the periphery thereof, and said outer contact being formed with a stamped portion for engaging said dog for preventing rotation of said enclosure in respect to said outer contact in one direction only to permit insertion of the contact in respect to a receptacle by turning the enclosure.

In witness whereof, I have hereunto subscribed my name.

LESTER KULP.
